(57) CLAIM

The ornamental design for an accessory pocket, as shown and described.

DESCRIPTION

FIG. 1 is a perspective view of the accessory pocket my design;

FIG. 2 is a front view thereof;

FIG. 3 is a side view thereof;

FIG. 4 is a side view thereof;

FIG. 5 is a front view thereof;

FIG. 6 is a back view thereof;

FIG. 7 is a side view thereof;

FIG. 8 is a top view thereof; and,

FIG. 9 is a bottom view thereof.

The dash broken lines in FIGS. 1-2 are for the purpose of illustrating environmental structure that form no part of the claim design. The dash broken lines in FIG. 6 are for the purpose of illustrating stitching.
